UNITED STATES PATENT OFFICE.

JAMES H. COFFMAN, OF COLUMBUS, OHIO, ASSIGNOR OF ONE-HALF TO
GRANT SHAW, OF COLUMBUS, OHIO.

CHAIR CONSTRUCTION.

No. 851,067.

Specification of Letters Patent.

Patented April 23, 1907.

Application filed November 16, 1906. Serial No. 343,668.

To all whom it may concern:

Be it known that I, JAMES H. COFFMAN, a citizen of the United States, residing at Columbus, in the county of Franklin and State of Ohio, have invented certain new and useful Improvements in Chair Construction, of which the following is a specification.

My invention relates to a chair construction and has for its object the provision of a chair constructed in such manner that the side, seat and back members of said chair, may be separately upholstered and when these parts are fastened together, the tacking which secures the upholstering in position will be invisible.

A further object of the invention is the provision of a chair constructed in the manner described, together with improved means for securing the several parts of said chair together.

Further objects and advantages of the invention will be set forth in the detailed description which now follows.

In the accompanying drawing, Figure 1 is a vertical section of a chair constructed in accordance with the invention, Fig. 2 is a transverse section upon line $z-z$ of Fig. 1, Fig. 3 is a detail view of the joint between the back and one of the side members, Fig. 4 is an edge elevation of the back, and Fig. 5 is an inside elevation of one of the side members, illustrating the upper rear corner of said side member.

Like numerals designate corresponding parts in all of the figures of the drawing.

Referring to the drawing, the numeral 5 designates the seat member of the chair. This seat member is in the nature of an inverted box. Tacked to the upper rear edge 40 of this seat member as at 6, is an upholstering fabric 7 which extends over the front edge of the seat portion and is tacked under the lower front edge 8.

The side members 9 and 10 of the chair, carry rockers 11 and 12 and these side members are secured to the box-like seat portion by screws 13. These side members are covered with an upholstering fabric 15 which is tacked beneath the lower edge of the side members as at 16 and extends over said side members and is tacked as at 17 to said side members at the point of their juncture with the seat portion 5.

The back 18 has offset portions 19 which overlie the upper rear corners of the side members. These side members are recessed as at 20 (see Fig. 3) and the inner side of said recess is closed by a plate 21 which is secured in position by screws 22. This recess 20 therefore, forms a socket adapted to receive 60 tenons 23 which are carried by the offset portions 19 of the back 18. This back is covered by an upholstering fabric 24, one end of which is secured beneath the lower rear edge of the back as at 25 and the other end of 65 which is secured to the back at its juncture with the upper rear corner of the seat portion as indicated at 26. The lower portion of the back is secured by screws or other fastening devices 27 to the seat portion 5.

By virtue of the foregoing construction, it will be seen that the two side members, the seat member and the back member may be separately upholstered before the chair is put together. This is very desirable, for it 75 enables the workmen to handle the parts more readily than would be the case if the chair were upholstered after it had been put together.

In putting this chair together, the two side 80 members are first secured to the box-like bottom portion. A transverse strip 31 is then secured in position between the two side members. The back is then slipped into such position that the tenons 23 enter the 85 sockets 20 of the side members. A second tenon 30 which is carried by the lower end of the back, enters a recess formed in the strip 31, the outer edges of the overhanging portions 19 then lying flush with the outer faces 90 of the side members. The fastening devices 27 are then placed in position, thereby securely tying all of the parts in position and bringing all of the tacking into such position that it will not be visible.

From the foregoing description, it will be seen that simple and efficient means are herein provided for accomplishing the objects of the invention, but while the elements shown and described are well adapted to serve the 100 purposes for which they are intended, it is to be understood that the invention is not limited to the precise construction set forth, but includes within its purview such changes as may be made within the scope of the 105 appended claims.

What I claim, is:

In a chair, the combination with a hollow box-like seat portion of considerable depth, of a covering of upholstering material secured to said seat portion about its upper edges, side members, supporting members carried by said side members, means for securing the side members to the seat member, a covering of upholstering material secured to said side members at their juncture with the seat portion and at their outer lower edges, a back portion having overhanging members, the outer edges of which lie flush with the outer faces of the side members, said side members having sockets formed in their upper rear edges, tenons carried by the overhanging members of the back adapted to enter said sockets, a transverse strip which extends between and is carried by the side

members, said strip lying close to the lower 20 rear edge of the seat member, a tenon carried by the lower edge of the back portion which enters a socket formed in said strip, and a covering of upholstering material which is secured to said back portion at its 25 juncture with the seat member and at its lower rear edge, the upholstering covering of the side members extending over the upper edges of said side members and the upholstering covering of the back extending over 30 the upper edge of the back, substantially as described.

In testimony whereof I affix my signature in presence of two witnesses.

JAMES H. COFFMAN.
